CLAIM

The ornamental design for a handheld electronic device with transparent shell, as shown and described.

DESCRIPTION

FIG. 1 is a front elevation view of our new design for a handheld electronic device with transparent shell;

FIG. 2 is back elevation view of FIG. 1;

FIG. 3 is a top plan view of FIG. 1;

FIG. 4 is a bottom plan view of FIG. 1;

FIG. 5 is a left side elevation view of FIG. 1;

FIG. 6 is a right side elevation view of FIG. 1; and,

FIG. 7 is a back perspective view of FIG. 1.

The broken lines immediately adjacent the claim, encompassing unshaded regions, represent the bounds of the claimed design while all other broken lines are directed to environment and are for illustrative purposes only; the broken lines form no part of the claimed design.

1 Claim, 3 Drawing Sheets
